DESIGN FOR A VENDING MACHINE

Harry S. Benjamin, Poughkeepsie, N. Y.

Application April 15, 1940, Serial No. 91,680

Term of patent 14 years

To all whom it may concern:

Be it known that I, Harry S. Benjamin, a citizen of the United States, residing at Poughkeepsie, in the county of Dutchess and State of New York, have invented a new, original, and ornamental Design for Vending Machines, of which the following is a specification, reference being had to the accompanying drawings, forming part thereof.

Figure 1 is a front elevational view of a vending machine, showing my new design;

Fig. 2 is a side elevational view of the same;

Fig. 3 is a plan view thereof; and

Fig. 4 is a perspective view of the same.

I claim:

The ornamental design for a vending machine, as shown.

HARRY S. BENJAMIN.
